UNITED STATES PATENT OFFICE

118,741

DESIGN FOR A MATCH BOOK

Herman Lieber, Bronx, N. Y.

Application October 9, 1939, Serial No. 87,584

Term of patent 3½ years

To all whom it may concern:

Be it known that I, Herman Lieber, a citizen of the United States, residing in New York city, in the county of Bronx and State of New York, have invented a new, original, and ornamental Design for a Match Book, of which the following is a specification, reference being had to the accompanying drawing, forming part thereof.

I claim:

The ornamental design for match book, as shown.

HERMAN LIEBER.
